ROUGHENING TOOL FOR THE WORKING OF LEATHER

Filed March 28, 1929

UNITED STATES PATENT OFFICE

ERICH SACHSE, OF PEGAU, AND OTTO MICHALK, OF FREITAL, GERMANY

ROUGHENING TOOL FOR THE WORKING OF LEATHER

Application filed March 28, 1929, Serial No. 350,520, and in Germany May 5, 1928.

In the manufacture of boots and shoes by glueing the parts together it is necessary to roughen the leather pieces at the glueing rims prior to applying the agglutinant or cementing medium in order to cause the pieces or parts to stick more strongly together. The roughening is generally effected by means of rotating disks bearing spikes or similar members, for instance such as used in connection with carding bands. The leather parts must be roughened only at their surface, as it can otherwise easily occur that pieces are torn out of them whereby the parts will be severely impaired. The degree of the roughening could be determined up to now, i. e. with the roughening tools employed up to now, chiefly only at random by pressing the leather more or less strongly against the respective tool, so that the roughening operation must be effected by clever workmen, especially if the leather is thin, but even particularly clever workmen are only seldom in the position to deliver a satisfying output.

The object of the present invention is to obviate the above-mentioned drawbacks, and the object sought to be attained is obtained by making the effective length of the roughening spikes or their equivalents adjustable or readjustable for instance by holding them between lamellæ over which only a small piece of every spike, etc. projects. The length of the projecting pieces of the spikes, etc. can be determined by shifting either these members in the lamellæ or these latter upon the spikes etc., according to the sort or quality etc. of the leather. As the lamellæ present a rigid surface for the leather parts the roughening work is considerably facilitated, in that the respective parts can be pressed down upon, and stretched over, whereby the spikes etc. are prevented from tearing pieces of the leather out of the leather parts treated.

In the case of the employment of carding bands the roughening device may be so designed that said bands can be easily exchanged, for which purpose they are supported upon sector-shaped members and are retained upon them by springs. There may

be eyes at the ends of the carding band pieces, and a common spring may be provided for a plurality thereof.

The invention is illustrated diagrammatically and by way of example on the accompanying drawings on which

Figure 1 is a plane of a roughening tool designed according to this invention,

Figure 2 is a longitudinal section therethrough;

Figure 3 shows some details, drawn to an enlarged scale;

Figure 4 is a side-view of another constructional form of the tool;

Figure 5 is a transverse section in the plane 5—5 of Figure 6, the cover (i, Fig. 6) being removed, and

Figure 6 is an axial section through the same modification in the plane 6—6 of Figure 5.

The body of the roughening tool, or of the carding band carrier respectively, consists of a disk *a* (Fig. 2) having on its two sides hubs *a'* and *a''*, each hub having a bore. The diameter of the bore of the hub *a''* is larger than the diameter of the bore of the hub *a'*, and the opposite portions of the two bores are connected with one another by a conical bore into which terminate two oppositely located radial bores, each of which encloses a plunger *b'* connected at its outer end with a circularly curved segment *b* contacting with one of the lateral surfaces of the disk *a*. The two segments *b* are drawn towards one another by helical springs *c*, as shown in Figs. 1 and 2, and each is provided on its outer circumferential face with a groove into which is placed a piece of carding band *e*, the ends of which are affixed to the respective segment by screws *m*.

The spikes *e'* of the carding band form rows, as usual, and between these rows are lamellæ *h* (Fig. 3) shaped in conformity with the shape of the spaces between said rows of spikes. The lamellæ pertaining to a segment *b* are connected with one another at one end by a bolt *h'* common to them, and at the opposite ends they are hinged at *h''* to the disk *a* so that they can be swung outwardly on these bolts *h''*.

n (Fig. 2) denotes a shaft having a conical portion *n'*, the shape of which corresponds to that of the conical bore portion above-mentioned. The device is shoved 5 upon said shaft, as shown in Fig. 2, and secured thereto by nuts *p*. The plungers *b'* are pressed outwardly by the conical shaft portion *n'* whereby also the segments *b* with the carding band portions are moved outwardly, counter to the pull of the springs *c*, in consequence whereof the pointed ends 10 *e'* of the spikes project more or less over the lamellæ *h*. How much the ends *e'* project depends upon how far the device has been shoved upon the shaft, and this can be determined by the position of an adjustable abutment nut *o* and the end nuts *p*.

How much the spike ends can be permitted to project depends upon the kind or quality 20 of the leather to be treated. The tension of the springs *c* must be such that the segments *b* are not moved radially outwards by the centrifugal force when the device is rotating so that the spike ends *e'* cannot 25 project more than intended, and is proper for the respective leather, which finds an abutment or support upon the lamellæ and into which the spike ends can penetrate only so much as they project over the lamellæ 30 whereby a detrimental action upon the leather by too strong roughening is very securely prevented. Owing to this manner of operation of the device unskilled hands can be employed for roughening even delicate 35 kinds of leather, and as no particular care is needed in the manipulation of the device the work proceeds quickly and the output is considerably greater than heretofore.

40 Roughening devices operating with carding bands require frequent renewal of the latter. Although the roughening work can be done by young hands, the renewal of the carding bands necessitates a certain skill, 45 and it is, therefore, necessary, that it be carried out by skilled persons. As the endless working band has been introduced also in the manufacture of boots and shoes it is 50 very disturbing if the renewal of the carding band requires an unduly long period of time, and it may be that the endless working band must be stopped which is highly undesired. On the other hand, the carding band must be securely attached to, and 55 properly stretched upon, its support and remain in this state while the roughening device is operating, the very important point to be observed being this that the number of revolutions of the device is about 2000 60 per minute, in consequence whereof the centrifugal force tends to throw the band outwardly and to lengthen it.

Although already the constructional form shown in Figs. 1-3 answers all practical 65 requirements, a still more improved con-

structional form intended especially for use in connection with a running band is shown in Figs. 4-6. This constructional form is so designed that the carding band pieces can be renewed quickly and reliably also by unskilled hands.

The body *a'* is provided with a sleeve *a'* by means of which the device can be attached to a shaft. *b'* are the sector-shaped members which are housed in the body *a'* and are firmly connected with the radial plungers *b''*, the inner ends of which are oblique, as shown in Fig. 6, and can be moved away from one another by the conical inner end of an adjusting screw *k* having a head *k'* with knurled circumference. This screw *k* can be fixed in its adjusted position by a nut *l*. When the screw *k* is turned in clockwise direction the plungers and the sectors are moved outwardly, and helical springs *c* connecting the sectors with one another and tending to draw them towards one another are put under increased tension.

The two carding bands *e* are stretched over the sectors *b'*, and eyes *f'* provided at one end of each of said bands are connected with one another by another helical spring *g* by which the two bands *e* are firmly pressed upon the said sectors. Eyes *f* are provided also at the other ends of the carding bands, and hooks *d* are provided at the correspondingly located ends of the sectors *b'*. Attaching the carding bands to the sectors is effected by inserting the ends of the spring *g* into the eyes *f'*, shoving the eyes *f* upon the hooks *d*, and then shoving the bands from the side of the nut *l* upon the sectors, it being understood that prior thereto the members *k* and *l*, as well as the cover *i*, have been removed. Then the cover is put in place. It is provided with two diametrically oppositely located pins engaging bores *h'* provided in the lamellæ and is secured in its proper position by the nut *l* after the screw *k* has been re-inserted into the body *a'*.

The operation of the carding bands is best when they do not lie perpendicularly with respect to the axis of the device or tool, but somewhat obliquely thereto. Thereby the entire leather surface contacting with the ends of the spikes is uniformly roughened, as the spikes over the whole breadth of the roughening surface will operate upon the leather without moving the leather laterally. A suitable oblique position of the bands can be attained by disposing the opposed faces of parts *a'*, *i* at oblique angles to the axis of the tool, as shown by lines *x-x* and *y-y* in Fig. 4, and also by positioning the pins of the carding bands so that they have a staggered arrangement over the working face of the tool, as will be readily understood. The carding bands then operate at an angle to the tool and give a better abrading effect. After the pins and lamellæ are

adjusted the nut *l* is tightened to cause disk *i* to tightly clamp the same in adjusted position.

We claim:

- 5 1. A roughening tool for the working of leather, comprising a rotatable support, rows of radially adjustable roughening spikes, means for holding them in operative position on said support, lamellæ positioned between said rows of spikes, and means for adjusting the spikes to vary the effective length of said spikes.
- 10 2. A roughening tool for the working of leather, comprising, in combination, a disk-shaped rotary body, circularly curved members so arranged as to be adapted to be shifted radially along said body or disk, springs so arranged as to tend to draw said curved members towards one another, means by which the said members can be moved away from one another, roughening spikes, and means holding them in operative position, these means being attached to, and supported by the said curved members.
- 15 3. A roughening tool for the working of leather, comprising, in combination, a disk-shaped rotary body, circularly curved members so arranged as to be adapted to be shifted radially along said body or disk, plungers guided in the said body and having said curved members affixed to their outer ends, means by which the said members can be moved away from one another, roughening spikes, and means holding them in operative
- 20 35 position, these means being attached to, and supported by the said curved members.
- 40 4. A roughening tool for the working of leather, comprising, in combination, a disk-shaped rotatory body, circularly curved members so arranged as to be adapted to be shifted radially along said body or disk, springs so arranged as to tend to draw said curved members towards one another, means by which the said members can be moved away from one another, carding band pieces bearing roughening spikes and being attached to, and supported by said curved members, and a spring maintaining said band pieces in proper position upon the said
- 45 50 curved members and keeping them under tension.
- 55 60 5. A roughening tool for the working of leather, comprising, in combination, a disk-shaped rotatory body, circularly curved members so arranged as to be adapted to be shifted radially along said body or disk, springs so arranged as to tend to draw said curved members towards one another, means by which the said members can be moved away from one another, carding band pieces bearing roughening spikes and being attached to and supported by said curved members, eyes at the ends of said band pieces, a hook provided at one end of each
- 65 of said curved members and engaging the

eye at one end of each band piece, and a spring connected at both ends with the other eyes of the carding band pieces and maintaining these latter in proper position upon the said curved members and keeping them under tension.

6. A roughening tool for the working of leather, comprising, in combination, with rows of roughening spikes, and with means for holding them in operative position, lamellæ arranged between said rows in an oblique position with respect to the driving axis of the tool, and means for adjusting the active length of said spikes with respect to said lamellæ.

7. A roughening tool for the working of leather, comprising, in combination, a rotatory tool body, a cover-like member arranged co-axially with said body, carding band pieces and supporting members for them, these pieces and members being arranged between said body and said cover, lamellæ located between the spike rows of said band pieces and being, together with them, arranged in an oblique position with respect to the tool axis, the faces of the said body and the said cover opposite said carding band pieces having the same obliquity as said lamellæ.

8. A roughening tool for the working of leather, comprising a rotative support, rows of radially adjustable spikes arranged at an oblique angle to the axis of the tool, means for holding the spikes in operative position on said support, lamellæ positioned between said rows of spikes, and means for adjusting the spikes to vary the effective length thereof.

In testimony whereof we affix our signatures.
